(57) **CLAIM**

The ornamental design for a thermostat housing, as shown and described.

DESCRIPTION

The present application is related to co-pending U.S. patent application Ser. No. 10/726,201, filed on December 2, 2003, entitled "Controller Interface With Multiple Day Programming", U.S. patent application Ser. No. 10/726,247, filed on December 2, 2003, entitled "Controller Interface With Menu Schedule Override", U.S. patent application Ser. No. 10/726,174, filed on December 2, 2003, entitled "Programmable Controller With Saving Changes Indication", U.S. patent application Ser. No. 10/725,826, filed December 2, 2003, entitled "Controller Interface With Separate Schedule Review Mode", U.S. patent application Ser. No. 10/726,243, filed December 2, 2003, entitled "Controller With Programmable Service Event Display", and U.S. application Ser. No. 10/726,245, filed December 2, 2003, entitled Controller Interface With Interview Programming.

The FIGURE is a front elevation view of a thermostat housing.

The portions, including letters and words, illustrated in broken lines on the figures are for illustrative purposes only and form no part of the claimed design.
